(57) **CLAIM**

The ornamental design for a vanity mirror, as shown and described.

DESCRIPTION

FIG. 1 is a first perspective view of a vanity mirror showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the vanity mirror thereof; and,

FIG. 10 is a perspective view of another state of the vanity mirror thereof.

The broken lines shown in the drawings depict portions of the vanity mirror that form no part of the claimed design.

1 Claim, 10 Drawing Sheets
